(57) **CLAIM**

The ornamental design for a feeding dish for multiple pets, as shown and described.

DESCRIPTION

FIG. 1 is a top perspective view of a feeding dish for multiple pets;

FIG. 2 is a front elevational view of the feeding dish;

FIG. 3 is a back elevational view of the feeding dish;

FIG. 4 is a left end elevational view of the feeding dish;

FIG. 5 is a right end elevational view of the feeding dish;

FIG. 6 is a top plan view of the feeding dish;

FIG. 7 is a bottom plan view of the feeding dish;

FIG. 8 is a top perspective view of an individual deep feeding bowl shown separately for clarity;

FIG. 9 is a front elevational view of the deep feeding bowl component in which the left end, right end and back elevational views are identical thereto;

FIG. 10 is a top plan view of the deep feeding bowl;

FIG. 11 is a bottom plan view of the deep feeding bowl;

FIG. 12 is a top perspective view of an individual shallow feeding bowl shown separately for clarity;

FIG. 13 is a front elevational view of the shallow feeding bowl in which the left end, right end, and back elevational views are identical thereto;

FIG. 14 is a top plan view of the shallow feeding bowl; and,

FIG. 15 is a bottom plan view of the shallow feeding bowl.

The broken line showing of a water supply bottle is not claimed.
